UNITED STATES PATENT OFFICE.

WILLIAM A. AINSWORTH, OF UTICA, NEW YORK.

DYEING-MACHINE.

1,348,974.

Specification of Letters Patent. Patented Aug. 10, 1920.

Application filed January 19, 1920. Serial No. 352,347.

To all whom it may concern:

Be it known that I, WILLIAM A. AINSWORTH, a citizen of the United States of America, residing at Utica, in the county 5 of Oneida and State of New York, have invented certain new and useful Improvements in Dyeing-Machines; and I do hereby declare the following to be a full, clear, and exact description of the invention, 10 such as will enable others skilled in the art to which it appertains to make and use the same.

This invention relates to winding and dyeing machines of the type shown in my 15 Patent No. 1,274,972, issued August 6, 1918. In machines of this character yarn thread or like fibrous material is wound from one holder to another and between said holders the yarn or like material is intermittently 20 brought into contact with a member saturated with liquid dye. The member which is saturated with dye may be of any suitable fabric material such as felt or the like. In practice it is desirable that this dye 25 carrying member shall be movable so as to bring different points of contact for the yarn as it is pressed thereagainst to receive the dye. One primary object of my invention is to provide a rotatable dye carrying 30 member which carries a felt around the same adapted to be partially immersed in the dye, the axis of rotation of said dye carrying member being located so that a rotation thereof continually changes the 35 position of the felt whereby, when the yarn is depressed into contact with the felt it strikes in different places thereon. This is desirable as otherwise the yarn would, in a short time, cut through the felt and render 40 it useless in operation. A further object of the invention is to provide means for continuously turning said dye carrying member during the operation of the machine. A still further object of the invention is to 45 provide the winding and dyeing machine and the dye carrying tube thereof with many novel features of construction and arrangement of parts for performing the random dyeing of yarn or like material in 50 the most effective manner without danger of ends of the yarn becoming caught in the mechanism or of remaining in contact with the dye soaked felt should the yarn at any time break during the process of winding 55 and dyeing. All of these features together

with many others not at this time specifically stated, will appear fully and in detail as understanding of the invention is had from the following description taken in connection with the accompanying drawing, in which;

Figure 1 is a fragmentary partial section and end elevation showing so much of a winding and dyeing machine as is necessary for an understanding of the invention, 65 which is applied thereto.

Fig. 2 is a fragmentary perspective view illustrating the principal working parts for accomplishing the dyeing.

Fig. 3 is a fragmentary enlarged plan 70 view showing one unit of the dyeing mechanism; and

Fig. 4 is a transverse section therethrough.

Like reference characters refer to like 75 parts in the different views of the drawing.

The usual winding machine used in knitting factories includes frame parts 1 and 2, as shown in Fig. 1, and a plurality of vertical spindles 3 are mounted for rotation 80 in the length of said frame each carrying a cone 4 at its upper end on which the yarn, thread or like material 4^a is wound. The yarn passes from a cone 5 to the receiving cone 4, the spindles being driven in any suitable manner as by a belt around the pulley 6 thereon. The yarn passes over a pin 7 projecting from a nut 8 which is threaded on a rod 9; the same also being 85 rotatably mounted and periodically reversed in its movements so as to carry the guide 10 up and down lengthwise of the cone 4 for properly winding the yarn thereon. All of this construction is old and well known and is fully shown in my prior patent 90 to which reference has been made.

The yarn as it passes to the cone 4 runs above a cylinder 11 in which a quantity of liquid dye is placed. This cylinder is carried by suitable brackets 12 attached at one 100 edge of the frame member 1. Brackets 14 are secured to the cylinder 11 and carry tension devices 13 at their outer ends, the yarn passing therethrough and thence across the dye cylinder and under a guide roller 15 105 before going over pin 7 so that the yarn as it passes across the cylinder is normally taut and lies a very short distance above the same. It is, of course, understood that the description made refers to one unit only 110

of a large number of units which may be in a winding and dyeing machine.

Directly under each length of yarn, thread or like material which passes across the cylinder 11, an opening 16 is made in the cylinder which is covered by a raised plate 17 detachably secured to the cylinder by screws or other suitable connections. This plate is provided with a slot 18 which

10 in length is parallel to the axis of the cylinder 11. Centrally of the slot a wire 19 is located and secured at its ends to the plate 17 adjacent the ends of the slot. A short post 20 is attached to the plate 17 and projects upwardly therefrom a short distance to one side of the normal path of movement of the yarn 4^a.

A stirrup 21 is inserted into the cylinder at each opening 16 the upper ends of the 20 sides thereof being hooked to connect with the sides of the opening 16 as shown in Fig. 4. A shaft 22 is rotatably mounted at its ends in and extends between the sides of the stirrup. On this shaft a roller is secured 25 around which two rings of felt are placed and attached. Said rings of felt extend upwardly through the slot 18 and the wire 19 passes between same. The dye in the cylinder 11 is kept high enough so that at least 30 the lower parts of said felt members immerse therein. A gear 24 is fixed on the shaft 22 and is in mesh with a spiral gear 25 fixed on a shaft 26 which extends the full length of the cylinder 11 there being one of 35 these spiral gears 25 on the shaft for each of the dyeing units, all turning with the shaft. One end of the shaft is equipped with a drive pulley 27 and may be turned by means of a belt 28 leading to any suitable driving mechanism.

Paralleling the cylinder 11 is a shaft 29 on which cam members 30 are secured so that one of the same lies above each of the horizontal portions of the yarn 4^a as it passes 45 from the tension 13 to the roller 15. This shaft has a pulley 31 at its end which may be driven by a belt 32. With each rotation of the shaft and with a cam of the form shown in Figs. 1 and 2 the yarn is twice depressed and brought into contact with the projecting portion of the felt 23 absorbing dye therefrom during the time that it is in contact therewith.

In operation the shaft 22 and attached 55 parts are continuously turning whereby the yarn 4^a strikes each time at a different point on the felt. This saves the felt from being cut through by the yarn and greatly lengthens the life of operation of said felts. The 60 wire 19 reinforces the felts and holds the same from being carried to one side and at the same time insures against any loose end of any yarn passing downwardly through the slot 18 and becoming entangled with the 65 mechanism and also insures against any

such loose end winding around or being carried by the felts downwardly to the cylinder. This might occur in practice any time should the yarn or like material break during the operation of winding and dyeing. Furthermore, the post 20 is of utility in that any loose or broken end may be wrapped around the same to hold it from contacting with the felt and thus absorbing a larger quantity of dye and breaking the 75 uniformity of the dye in a length of yarn or like material. In addition these dyeing units for the machine are all of the same kind and may be readily interchanged if necessary and it is required only that duplicates be made for the several units in the length of the machine, this greatly reducing the cost of manufacture. The wire 19 keeps the felts free from cuts and with this construction a new felt may be put on at 80 any time.

I have shown the axis of the shaft 22 parallel to the length of the yarn 4^a but the invention is not to be considered as limited thereto as it is obvious that the angle of 90 the shaft to the yarn may be widely varied. Various other changes may be resorted to without departing from the invention which is defined in the appended claims and I, accordingly, consider myself entitled to all 95 modifications of structure which fall within the scope of the claims defining the invention.

I claim:

1. In a dyeing machine, means to transfer 100 thread, yarn or like material from one holder therefor to another, a reservoir for coloring matter over which said material moves in passage, a roller mounted for rotation in said reservoir and projecting 105 above the same, said roller being provided with liquid absorbing material around the same, means for continuously driving said roller, and means for intermittently pressing said thread, yarn or the like into contact with the liquid absorbing material, substantially as and for the purposes described.

2. In a dyeing machine, a container for liquid coloring matter, a roller mounted for rotation in said container and projecting 110 slightly above the same, said roller having liquid absorbing material around it, means for continuously driving said roller, means for carrying a continuous length of thread, yarn or the like over the container and said 115 roller, and means for intermittently depressing thread, yarn or the like into wiping contact with the material on the roller, said material striking the liquid absorbing material at different points on each depression thereof, substantially as described.

3. In a dyeing machine, a container for liquid coloring matter provided with an opening in the upper side thereof, a stirrup extending into the opening, a shaft rota- 120

- tably mounted between the sides of the stirrup, a roller on said shaft having a liquid absorbing member entirely around it, means for driving said shaft, a plate covering the opening in the container and formed with a slot through which the upper portion of the roller and material thereon projects, means for carrying a continuous length of thread, yarn or the like across and above the roller, and means for intermittently depressing said thread, yarn or the like into contact with the liquid absorbing member on the roller, substantially as described.
- 15 4. In combination, a container for liquid coloring matter having an opening in the upper side thereof, a plate covering said opening and provided with a slot therein, a roller mounted within the container and having its upper portion projecting through the slot slightly above said plate, liquid absorbing material secured on and around the roller, means for continuously turning the roller, means for passing a continuous length 20 of thread, yarn or the like across the container and slightly above the roller, and means for intermittently pressing said thread, yarn or the like into wiping contact with the liquid absorbing material on the roller, substantially as described.
- 25 5. In combination, a container for liquid coloring matter having an opening in the upper side thereof, a plate provided with a slot attached to the container over said opening, a roller rotatably mounted within the container and extending at its upper portion through the slot, a wire attached to the covering plate at the ends of the slot and extending lengthwise of said slot, 30 and two rings of liquid absorbing material secured to and around the roller between which said wire is located, substantially as and for the purposes described.
- 35 6. In combination, a container for liquid coloring matter, means rotatably mounted therein and projecting slightly above the upper edge of the container, said means including liquid absorbing material, means for passing a continuous length of thread, 40 yarn or the like over said container, means intermittently depressing said thread, yarn or the like into wiping contact with said liquid absorbing material, and a post projecting upwardly from the container a short distance from the normal line of travel of said thread, yarn or the like, substantially as and for the purposes described.
- 45 7. In combination, a container for liquid coloring matter provided with an opening in the upper side thereof, a cover plate for said opening having a slot therein, a stirrup extending through said opening into the container, a shaft mounted between the sides of the stirrup, a roller on the shaft directly below the slot in the cover plate, 50 said roller having liquid absorbing material attached entirely around the same, a second shaft having its axis located at an angle to the axis of the first shaft, means to drive said first shaft by the second shaft, means to continuously drive the second shaft, means for carrying a continuous length of thread, yarn or the like across the container and above the roller, and means for intermittently depressing said yarn, 55 thread or the like into contact with the liquid absorbing material on the roller, substantially as described.
- 60 8. In combination, a container for carrying liquid coloring matter provided with an opening in the upper side thereof, a shaft extending lengthwise of the container, a stirrup passing through said opening into the container, a second shaft rotatably mounted between the sides of the stirrup, 65 gearing connections between the first and second shafts, a plate provided with a slot therein attached to the container over said opening, a wire attached to the plate and passing from one end to the other of the slot, a roller on the second shaft directly below the slot, and two rings of liquid absorbing material secured around the roller and projecting through the slot, one at each 70 side of said wire, substantially as and for the purposes described.
- 75 9. In testimony whereof I affix my signature.

WILLIAM A. AINSWORTH.
